J. L. NILSON,
TIRE PUMP,
APPLICATION FILED OCT. 3, 1914.

1,191,531.

Patented July 18, 1916.

UNITED STATES PATENT OFFICE.

JOHAN LUDVIG NILSON, OF CHICAGO, ILLINOIS.

1,191,531. Specification of Letters Patent. Patented July 18, 1916.

Application filed October 3, 1914. Serial No. 864,736.

To all whom it may concern:

Be it known that I, JOHAN L. NILSON, a citizen of the United States, residing at Chicago, in the county of Cook and State 5 of Illinois, have invented certain new and useful Improvements in Tire-Pumps, of which the following is a specification.

My invention relates to tire pumps and has particular reference to special constructions for automobiles where the pump is mounted on the running board and designed to be compactly folded up when not in use.

The object of the invention is to provide certain improvements in this type of pump 15 including in the construction a firmer mounting on the running board, a more secure support of the pump while being operated, greater convenience and more saving of time in adjusting the folding lever into 20 operative as well as folded position, a more economically constructed pump cylinder easily assembled and taken apart, protection of the cylinder against being dented without the provision of special parts for such 25 protection and enabling the use of iron heads for a brass cylinder, and the several other advantages in the construction which will appear from the hereinafter detailed description.

30 In the accompanying drawing—Figure 1 is a perspective view of an automobile running-board pump embodying my invention, the dotted lines indicating folded or inoperative position of the handle. Fig. 2 is a 35 longitudinal and vertical section of the pump mounted on a broken away portion of running board and having a part of its handle broken away. Fig. 3 is a section taken substantially on line 3—3 on Fig. 2. 40 Fig. 4 is a section taken substantially on line 4—4 of Fig. 1. Fig. 5 is a section taken substantially on line 5—5 of Fig. 1. Fig. 6 is a section taken substantially on line 6—6 on Fig. 5.

45 In the views 2 represents a section of automobile running board and 3 is the base for the pump. This base has on its rear portion an upstanding lug 4 to which at 5 is pivoted a lug 6 which projects from the 50 central portion of the rear head 7 of the pump cylinder 8 having a front head 9 through which the usual piston rod 10 passes. On the inner end of the rod, or 55 within the cylinder, is mounted in the usual manner the usual fiber cup or disk between

the edges of which air is admitted on the back stroke through the air inlet 12. Cast integral with the head 7, which together with the head 9, may be of cast iron while the cylinder 8 is of brass, is a lug 13 in the outer end of which is a counter bore 14 for a spring 15. A smaller bore, or air-outlet 16 leads from the bottom of the counterbore to the interior of the cylinder and is controlled by a ball valve 17 interposed between 60 the spring and the bore 16. By means of any suitable form of coupling 18 an air-tube 19 is connected with the lug 13.

In order to enable the construction of the cylinder 8 of a thinner than usual gage of 70 brass to lessen the cost and to obviate the expense of brass heads 7 and 9 which are usually soldered to the brass cylinder 8 and at the same time provide protecting guards for the comparatively thin cylinder 8 to prevent its being accidentally dented in the course of ordinary handling of the pump, the heads 7 and 9 are secured to the cylinder by means of connecting rods 20, 21 and 22 each of which has a head 23 on one end and 75 a nut 24 threaded on the opposite end, a suitable fiber ring or gasket 25 being interposed between the rear end of the cylinder and the head 7 to obtain an air-tight joint at this end. On the forward end of the base, 80 which has a form which permits its construction by either the die or molding process, is a bearing lug 26 to which at 27 is pivoted a double elbow form lever 28 at the lower elbow 29 of which is pivoted at 30 85 the piston-rod 10. The dotted lines in Fig. 1 indicate the relation of this lever to the cylinder when in folded position. In this folded position a portion 31 of the lever extends horizontally from the pivot 27 toward the cylinder while a portion 32 rises vertically and projects the body of the lever above the cylinder where said body, in folded position overlies and is parallel with the cylinder. On the free end of the lever 28 is 90 a lug or socket portion 33 which is engaged by a hollow end or socket 34 of a lever extension or handle 35. When the lever 28 is folded over the cylinder the lug 33 projects upwardly at an angle, as shown in Figs. 1 95 and 6. The socket 34 projects from one side of the handle so that the lug 33 may enter the socket opening from either of its ends. When the lever 28 is folded over the cylinder the handle 35 may have its position re- 100 105 110

versed, as indicated in Figs. 1, 5 and 6, to make it lie alongside of the lever 28 and to not project substantially beyond the ends of the base 3 in an obstructing manner. In lever extensions it is usual to fasten the extension or handle by means of a short bolt or other device which takes time to adjust. The inclination of the lug 33 obviates the necessity of such fastening because jarring of the parts tend to keep the socket and lug engaged. It also obviates the weakening of the parts by providing a bolt hole at this joint, while the removal of the handle from operative position and reengaging it in folded position may be done instantaneously.

The base 3 is fastened to the running board 2 by means of an ordinary tire clamp 36 usually carried in the driver's kit. In the base 3 is a channel portion 37 which receives the upper jaw of the clamp and extends across the base so that the end of the screw 38 of the clamp may be brought to bear against the median line of the base and thus prevent its tipping when the pump is actuated, as when the jaws of the clamp engage only one edge or side of the base. In the arrangement shown the lever is in the same vertical plane as the rod 10 which also prevents the tendency to tip the pump when force is applied to the lever, as where the lever is arranged to one side of the rod 10. Supporting feet or lugs 39 and 40 are on the bottom of the base 3 and are designed to even contacting supporting parts that engage the running board.

Having thus described my invention, I

claim as new and desire to secure by Letters Patent—

1. A running board tire pump comprising a base, means for clamping said base to the running board, a pivotally mounted pump cylinder, and an operating lever and extension or handle therefor arranged to fold over on the pump cylinder, said lever and handle having a lug and socket arrangement, said lug being when the lever is in inoperative position upwardly inclined to prevent jarring apart of the lug and socket engagement.

2. The combination with a pump of the class described, of an operating lever and handle separable from each other and engageable with each other in reverse relation to fold over onto the pump cylinder, and loosely interengaging means upon said lever and handle for supporting one upon the other in their folded position.

3. The combination with a pump of the class described, of a pivotally mounted pump cylinder, a lever and detachable handle therefor, means for reversibly engaging said lever and handle without fastening same to each other, and guards for said pump cylinder to protect it against indentations.

In testimony whereof I have hereunto set my hand in the presence of two subscribing witnesses.

JOHAN LUDVIG NILSON.
